UNITED STATES PATENT OFFICE.

ANDREW J. BURTON, OF DENVER, ALABAMA.

MOTOR.

SPECIFICATION forming part of Letters Patent No. 732,705, dated July 7, 1903.

Application filed November 17, 1902. Serial No. 131,760. (No model.)

To all whom it may concern:

Be it known that I, ANDREW J. BURTON, a citizen of the United States, residing at Denver, in the county of Tallapoosa and State of Alabama, have invented certain new and useful Improvements in Motors, of which the following is a specification.

This invention belongs to the type of mechanisms for developing power to be used in driving machinery of every sort.

In accordance with this invention force is readily converted into available energy, opposing forces coöperating to produce a resultant force representing the usable power.

15 The motor comprises a wind-wheel, a system of levers including toggles having opposite members connected to levers attached, respectively, to the wind-wheel and the shaft, means for applying power to the toggles to effect rotation of the shaft, and a casing housing the parts and provided with inlets for directing the wind upon the wings of the fan.

20 For a full description of the invention and the merits thereof and also to acquire a knowledge of the details of construction of the means for effecting the result reference is to be had to the following description and drawings hereto attached.

25 While the essential and characteristic features of the invention are susceptible of modification, still the preferred embodiment of the invention is illustrated in the accompanying drawings, in which—

30 Figure 1 is a perspective view of a motor embodying the invention, a portion of the casing being broken away to show the operating parts. Fig. 2 is a horizontal section about in the plane of the wind-wheel, the toggles and levers being shown in full lines.

35 Corresponding and like parts are referred to in the following description and indicated in both views of the drawings by the same reference characters.

40 The motor may be mounted in any convenient way, depending upon the location and specific purpose, and, as shown, it is supported by means of a tower 1, such as commonly employed in connection with windmills. The shaft 2 is vertically arranged and mounted in suitable bearings, and power is adapted to be taken therefrom in any accustomed way. The wind-wheel is mounted loosely upon the

shaft 2 and comprises a hub 3 and wings 4, said wings being concavo - convex and arranged with their convex sides facing in the same direction. The wind - wheel may embody any number of wings, and for the sake of simplicity two only are shown in the drawings and are oppositely disposed, the hollow side of one facing the wind and the convex side of the other facing away from the wind. As stated, the wind-wheel is loosely mounted upon the shaft 2 and is connected therewith by means of a spiral spring 5, one end of the spring being attached to the hub 3 and the opposite end to the shaft 2. An arm 6 projects horizontally from the shaft 2, and a lever 7 is pivoted at one end thereto and extends transversely of the motor, so as to project upon opposite sides of the shaft about 70 an equal distance. A companion lever 8 is pivoted at one end to the lever 7, and its opposite end is connected to the wind-wheel by means of a post 9, pendent from a wing thereof. The levers 7 and 8, arranged substantially as set forth, admit of the wind-wheel having a limited vertical play and independent rotary movement, the levers being sufficiently elastic to move laterally at the ends connected with the parts 6 and 9. Toggles 75 10 and 11 are arranged upon opposite sides of the shaft 2 and in a plane approximately at a right angle to the plane of the levers 7 and 8. A lever of the toggle 10 is connected with the lever 8 by means of a rod 12 or like part, and a lever of the toggle 11 is similarly connected to the lever 7 by means of a rod 13. The outer ends of the toggles are pivotally connected to collars 14 and 15, one above and the other below the plane of the wind - wheel. The 80 lower collar 15 is supported upon a shoulder or stop 16, applied to or forming a part of the shaft 2 and constituting a fixed point of resistance. The upper collar 14 is movable, so as to have play upon the shaft 2, this being 85 essential to the operativeness of the motor. It is contemplated to apply power to the collar 14, so as to cause movement of the shaft in order to operate the machine or part to be driven. This power may be applied in any 90 convenient way, and, as shown, a sleeve 17 is loosely fitted upon the shaft 2 and is adapted to exert an end thrust against the part 14. A lever 18 is pivoted at one end to a post 19,

projected upward from either the casing or the tower 1, said lever 18 being horizontally arranged and pivoted to the sleeve 17. A cord or rope 20 is connected to the free end 5 of the lever 18 and extends within convenient reach and is adapted to be pulled upon or to receive a weight or other force representing the power to be expended for compressing the toggles, whereby the wind-wheel and shaft 10 tend to move in opposite directions, and inasmuch as these forces are of unequal strength the weaker force yields to the superior force. Hence the shaft 2 rotates in a direction corresponding to the application of the stronger 15 force. By reason of the concavo-convex construction of the wings the air resistance to the backward rotation of the wheel is far in excess of the air resistance to the forward rotation, and this, together with the inertia of the 20 wheel, results in a forward rotation of the shaft as the lever 18 is operated in the manner stated. Power is applied to the lever 18 at such times only when there is no wind.

In order to utilize the force of the wind for 25 operating the motor, a casing 21 surrounds the working parts and is attached to the support or tower 1 and is provided with a series of spouts or inlets 22, which are adapted to direct jets of air against the wings 4 and set 30 the engine in motion, as will be readily comprehended.

Having thus described the invention, what is claimed as new is—

1. In a motor of the character described, a 35 shaft, a wheel mounted coaxially with said shaft, levers located in a plane about paral-

lel with the plane of the wheel and pivoted together at one end and having the opposite end connected to, respectively, the said wheel and shaft, and oppositely-disposed toggles 40 connected to the respective levers and tending to move the wheel and shaft in opposite directions upon the application of power thereto, substantially as described.

2. In a motor of the character described, a 45 shaft, a wheel loosely mounted upon the shaft and connected by a spring thereto, companion levers connected to each other and to said wheel and shaft, and toggles arranged in a plane at a right angle to the said companion 50 levers and having corresponding toggles connected to the respective levers, substantially as set forth.

3. In combination, a shaft, a wind-wheel loosely mounted thereon and connected thereto by means of a spring, companion levers connecting the wind-wheel with the shaft, oppositely-disposed toggles connected to the respective members of said companion levers, means for applying power to the toggles to 60 move the wind-wheel and shaft in opposite directions, and a casing for closing the wind-wheel and adjunctive parts and provided with inlets for the air, substantially as specified.

In testimony whereof I affix my signature in presence of two witnesses.

ANDREW J. BURTON. [L. S.]
